United States Patent Office.

EDWARD A. HYDE, OF ANN ARBOR, MICHIGAN.

Letters Patent No. 97,512, dated December 7, 1869.

IMPROVED SHOT AND BULLET-MACHINE.

The Schedule referred to in these Letters Patent and making part of the same.

To all whom it may concern:

Be it known that I, EDWARD A. HYDE, of Ann Arbor, in the county of Washtenaw, and State of Michigan, have invented a new and improved Mode of Making Shot and Bullets; and I do hereby declare that the following is a full and exact description thereof, reference being had to the accompanying drawings, and to the letters of reference marked thereon, making a part of this specification.

The old method of making shot is by letting melted lead, in a divided state, fall from high towers.

The nature of my invention consists in throwing melted lead into the air, in a divided state, by means of a rotating wheel or arm. I thus secure the desired time for cooling or hardening in a globular form without the use of towers.

To enable others skilled in the art to make and use my invention, I will proceed to describe its construction and operation.

Over any arch or furnace, I place a cylindrical heater, of cast-iron or other metal, A, having an oblong head, B B, from which rises the rim C C, and in which rotates the wheel D, driven by the shaft E.

The rim C has an opening F, provided with the sharp lip G.

The rim of the wheel D is provided with the notches or holes a a, and the inner face of the wheel has the radiating vanes or arms b b b.

Figure 1 is a perspective view of the end of the heating-cylinder, showing the manner of attaching the wheel.

Figure 2 is a sectional side view of the same, showing how the melted lead enters the wheel D.

Figure 3 shows the back side of the wheel D, and the manner in which it sets in the rim C C.

Figure 4 is a perspective view of the wheel D, showing the vanes or arms b b b on the back side, and also the notched rim, with notches a a a.

Figure 5 shows the manner in which the melted lead, in a divided state, is thrown into the air, and descends into the tub of oil M.

A is the melting-cylinder.

B B, one of its heads.

C C, the rim in which sets the wheel D.

E is the shaft by which the wheel is rotated.

F is an opening in the rim C C, from which the lead escapes through a a by centrifugal force.

G is the lip which cuts off the jets of lead as they come from a a, dividing them, so as to form globules.

H is an opening through the head B B, allowing the lead to enter the wheel.

J is an enlargement of the cylinder A, allowing the hot lead to come opposite the entire face of the wheel, to keep it hot.

K K is the lead.

L L show the flight of the globules from the wheel to the tub of oil M.

a a a a are notches or holes through the rim of the wheel.

b b b b are vanes or arms, which cause the lead in the wheel to revolve with it, thus acquiring the necessary centrifugal force to cause the lead to press out at the holes a a a when they come opposite F.

The operation of my invention is as follows:

The heater being filled with lead, and fire applied sufficient to melt and keep the lead in a sufficiently-fluid state, I cause the wheel D to revolve rapidly. Then I remove the cap from the opening F in the rim C C, and the lead, in jets, is forced out at the openings a a a by centrifugal force, the lip G cutting off these jets into exact atoms, which fly into the air on a tangent to that part of the circumference where the opening in the rim C C begins.

If the velocity of my wheel is sufficient to throw the globules twenty-five feet into the air, it is evident that I thus secure as long a time for each globule to cool as I would from a tower of about one hundred and twenty-five feet in height.

The wheel D may be made deeper, so as to accommodate several rows of the holes a a a.

Another method of constructing the wheel D is to make it similar to a wagon-wheel when the felloes are removed—that is, having simply the hub and spokes. In this case, both spokes and hub are hollow, the latter setting over the opening H. This form of wheel may be used in combination with the rim C, or without the rim, by having the outer end of each arm or spoke opened at a given point in the circle by an eccentric, cam, or other device, so as to allow a given quantity of lead to fly out, and then closed again, until the same point is reached in the next revolution.

The actual contact of the wheel D with the cylinder-head B is not necessary. It may be separated any required distance from the cylinder A by a pipe connecting the opening H with a similar opening in a secondary head, having the rim C, and setting over the back of the wheel D. So also the wheel, when made with hollow hub and spokes, may be separated from the cylinder by a pipe.

What I claim, and desire to secure by Letters Patent, is—

1. The rotating wheel D, constructed as described, in combination with the cylinder A, as set forth.

2. In combination with the rotating wheel D, the rim C C, provided with the opening F and the cutting-lip G, substantially as set forth.

EDWARD A. HYDE.
